(57) CLAIM

The ornamental design for a water cart, as shown and described.

DESCRIPTION

FIG. 1 is a front perspective view of a water cart, with a front door closed;

FIG. 2 is a front perspective view of the water cart, with a front door open;

FIG. 3 is a front view of the water cart;

FIG. 4 is a rear view of the water cart;

FIG. 5 is a left side view of the water cart;

FIG. 6 is a right side view of the water cart;

FIG. 7 is a top view of the water cart;

FIG. 8 is a bottom view of the water cart; and,

FIG. 9 is a rear perspective view of the water cart. Broken lines show portions of the water cart that form no part of the claimed design.
